CLAIM

The ornamental design for a lawn cultivator and seeder as shown and described.

DESCRIPTION

FIG. 1 is a front bottom perspective view of a first embodiment of the lawn cultivator and seeder;

FIG. 2 is a front bottom perspective view thereof showing the funnel/safety cover in a first alternate position;

FIG. 3 is a back top perspective view thereof;

FIG. 4 is a back top perspective view thereof showing the funnel/safety cover and top cap in a second alternate position;

FIG. 5 is a bottom view thereof;

FIG. 6 is a top view thereof; and

FIG. 7 is a left side view thereof;

FIG. 8 is a front view thereof;

FIG. 9 is a right side view thereof;

FIG. 10 is a back view thereof; and,

FIGS. 11A and 11B are a front view of a second embodiment of the lawn cultivator and seeder.

The front bottom perspective, back top perspective, bottom, top, left side, right side, and back views of the second embodiment of the lawn cultivator and seeder have been omitted as they are the same as the views in FIGS. 1-7 and 9-10 other than the overall length of the article as illustrated in FIGS. 11A and 11B. The broken lines in the drawings illustrate portions of the lawn cultivator and seeder that form no part of the claimed design. The break lines in FIGS. 1-4 and 7-10 indicate that the appearance of any portion of the lawn cultivator and seeder between the break lines forms no part of the claimed design.
